UNITED STATES PATENT OFFICE.

JOHN THOMAS LISTER, OF CLEVELAND, OHIO.

DESIGN FOR AN INCANDESCENT-LAMP BULB.

SPECIFICATION forming part of Design No. 28,931, dated June 28, 1898.

Application filed April 28, 1898. Serial No. 679,146. Term of patent 14 years.

To all whom it may concern:

Be it known that I, JOHN THOMAS LISTER, a citizen of the United States of America, and a resident of Cleveland, county of Cuyahoga, 5 State of Ohio, have invented a certain new and useful Design for Incandescent-Lamp Bulbs, of which the following is a specification.

Figure 1 is a vertical section of a bulb, showing my design. Fig. 2 is a plan view of the same. Fig. 3 is a plan view showing neck in section on line X X, Fig. 1.

As shown in the drawings, the leading or material feature of my design consists of a 15 cylindrical body A, provided with hemispherical extremities B B. At the upper extremity the neck C is inserted centrally and joined to the hemispherical portion by means of curves

D. A reentrant stem E is cylindrical in shape and centrally turns backward to form a short 20 tube F, closed at the upper extremity by curved lines G, all connecting lines being curved between the parts. The lower extremity is perfectly plain and smooth in all respects.

Having described my invention, what I claim as new, and desire to secure by Letters Patent, is—

The design for an incandescent-lamp bulb, as herein shown and described.

Signed by me, at Cleveland, Ohio, this 26th day of April, 1898.

JOHN THOMAS LISTER.
